(57) CLAIM

The ornamental design for a deodorizing machine, as shown and described.

DESCRIPTION

FIG. 1 is a perspective view of a deodorizing machine, showing my new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof.

FIG. 7 is a bottom plan view thereof; and,

FIG. 8 is a cross-sectional view, taken along line 8-8 of FIG.
4.

The broken line portions of the design are included to show unclaimed portions and form no part of the claimed design.
